CLAIM

I claim the ornamental design for a strip light, as shown and described.

DESCRIPTION

FIG. 1 is a top perspective view of a strip light;
FIG. 2 is an elevational right view thereof;
FIG. 3 is a left elevational view thereof;
FIG. 4 is a front elevational view thereof;
FIG. 5 is a back elevational view thereof;
FIG. 6 is a top plan view thereof; and,
FIG. 7 is a bottom plan view thereof.
The broken lines shown in FIG. 7 illustrate portions of the strip light that form no part of the claimed design.
